UNITED STATES PATENT OFFICE.

MAX SHOLL, OF CHICAGO, ILLINOIS.

COLLAPSIBLE DRINKING-CUP.

957,264.

Specification of Letters Patent. Patented May 10, 1910.

Application filed December 1, 1909. Serial No. 530,892.

To all whom it may concern:

Be it known that I, MAX SHOLL, a citizen of the United States, residing at Chicago, county of Cook, and State of Illinois, have 5 invented certain new and useful Improvements in Collapsible Drinking-Cups, of which the following is a specification.

My invention relates to drinking cups and more specifically to that class thereof so constructed as to adapt the same to be collapsed or folded into a small compass for convenience in storage and transportation.

The object of my invention is the provision of a drinking cup of the character 15 mentioned which can be folded so as to adapt the same for carriage in the pocket or an ordinary hand purse, which will be effectual in use, and of strong, durable and comparatively simple construction.

20 Other objects will appear hereinafter.

With these objects in view my invention consists in a collapsible drinking cup characterized as above mentioned and in certain details of construction and arrangement of 25 parts all as will be hereinafter fully described and particularly pointed out in the appended claim.

30 My invention will be more readily understood by reference to the accompanying drawings forming a part of this specification, and in which,

Figure 1 is a perspective view partially in section of my improved drinking cup showing the same in distended position, Fig. 2 35 is a similar perspective thereof in collapsed position, Fig. 3 is a slightly enlarged sectional detail taken on line $\alpha-\alpha$ of Fig. 2, Fig. 4 is a perspective view of the comprising members of the cup proper unfolded, 40 Fig. 5 is a slightly enlarged horizontal section taken on line $y-y$ of Fig. 1, Fig. 6 is a slightly enlarged section on line $z-z$ of Fig. 5, and Fig. 7 is a perspective view illustrating the method of constructing the body 45 of the cup.

Referring now to the drawings, 1 indicates the inner or body portion of the cup. Comprised in said portion are preferably two 50 similar originally flat substantially square flexible members 2, the same being formed preferably of a chemically pure suitable waterproof paraffin or oiled paper. Interposed centrally between said members 2 is a piece of chemically pure waterproof fabric 3 of dimensions considerably less than 55 those of the members 2. The peripheral

edge portions of said members 2 and 3 are bent upwardly and crimped to form the lateral substantially perpendicular, preferably slightly flaring, walls 4 of the cup. In- 60 closing the body 1, the same being se- cured as by stitching to the upper edge thereof is an outer tubular casing 5 of a foldable nature and possessing more rigidity and firmness than the members 65 2 and 3. In the formation of the body 1 a templet 6 of a frusto-conical shape is preferably employed. With such employ- 70 ment, the members 2 and 3 relatively ar- ranged as before stated, are placed centrally 75 upon the upper extremity of said templet. The peripheral edge portions of said mem- bers are then bent downwardly, as shown in Fig. 7, and crimped, this being readily ef- fected by the fingers, at preferably four 75 points designated as 7, as clearly shown in Fig. 5, into conformity with the contour of said templet. This being done the tubular casing 5 is slipped over said templet and members 2 and 3, whereupon the latter and the former, upon being removed from the templet, may be saved together as before stated. The upper edges of the members 2, in this arrangement it will be found, project 80 in a ragged manner above the upper edge of the casing 5. By means of a pair of scissors or a like tool these edges may evidently be readily trimmed to register with said edge of said casing, as illustrated in the drawings. Said casing as seen preferably projects be- 85 low the lower extremity of the body 1, whereby the bottom of the latter is protected against injury or puncture.

With the provision of a cup of such con- struction, the same by first upwardly indent- 90 ing the bottom of the body 1 as shown in Fig. 3, may be readily longitudinally col- 95 lapsed to a position as shown in Fig. 2, in which position the same may be readily in- 100 serted into the pocket or any other suitable place for carriage. By forming the body of the cup of two thicknesses of paper and the bottom thereof with an additional reinforce- 105 ing thickness of fabric, the same will evi- 110 dently not be readily susceptible to rupture or puncture, because of folding or creasing thereof. Further by the provision of the outer casing 5, the cup will be rendered rigid against vertical collapsing, also additional protection for the body 1 will thereby be provided.

While I have shown what I deem to be the

preferable form of my device I do not wish to be limited thereto as there might be various changes made in the details of construction and the arrangement of parts without departing from the spirit of the invention comprehended within the scope of the appended claim.

Having described my invention what I claim as new and desire to secure by Letters 10 Patent is:

A collapsible drinking cup comprising an inner flexible substantially cylindrical body, said body consisting of a bottom, and lateral walls formed integral with said bottom, said 15 bottom and lateral walls being formed of two originally flat sheets of flexible waterproof paper and an intermediate sheet of

water-proof fabric interposed between the bottom-forming portions of said paper sheets, the said intermediate sheet being of 20 less size than said other sheets, the peripheral edge portions of said sheets being crimped to form said lateral walls of said body; and a longitudinally foldable relatively rigid tubular casing inclosing said 25 body and secured thereto at the upper edge thereof, substantially as described.

In testimony whereof I have signed my name to this specification in the presence of two subscribing witnesses.

MAX SHOLL.
